(57) **CLAIM**

The ornamental design for an elevator wall surface having decorative pattern, as shown and described.

DESCRIPTION

The sole FIGURE is an orthographic view of an elevator wall surface having decorative pattern according to the claimed design.

The broken-lines illustrate environmental structure and form no part of the claimed design. In particular, the broken lines showing the side, top and bottom walls of the elevator cab are flat and unornamented.

The dash-dot-dash broken line defines a boundary of the claimed design and is not an ornamental part of the design itself.
